United States Patent Office

Des. 225,181
Patented Nov. 21, 1972

225,181

MOTION PICTURE VIEWER

James R. Skinner, Cupertino, Mark O. Uitz, Mountain View, and Paul W. Hait, Saratoga, Calif., assignors to F.J.L. Corporation, Mountain View, Calif.

Filed Oct. 5, 1970, Ser. No. 25,323

Term of patent 14 years

Int. Cl. D16—01
U.S. Cl. D61—1

FIG. 1 is a side elevational view of a motion picture viewer showing our new design;

FIG. 2 is a side elevational view of a motion picture viewer opposite the side shown in FIG. 1;

FIG. 3 is a rear elevational view of the motion picture viewer;

FIG. 4 is a front elevational view of the motion picture viewer;

FIG. 5 is a bottom plan view of the motion picture viewer.

We claim:

The ornamental design for a motion picture viewer, as shown.
